G. F. RENDALL.

REDUCTION PLANT FOR TREATMENT OF METALLIC SANDS OR CONCENTRATES.

APPLICATION FILED JUNE 23, 1908.

986,086.

Patented Mar. 7, 1911.

UNITED STATES PATENT OFFICE.

GEORGE FREDERICK RENDALL, OF NEW YORK, N. Y.

REDUCTION PLANT FOR TREATMENT OF METALLIC SANDS OR CONCENTRATES.

986,086.

Specification of Letters Patent.

Patented Mar. 7, 1911.

Application filed June 23, 1908. Serial No. 440,048.

To all whom it may concern:

Be it known that I, GEORGE FREDERICK RENDALL, a citizen of the United States, residing in the city and county of New York, State of New York, have invented a new and useful Reduction Plant for Treatment of Metallic Sands or Concentrates, of which the following is a specification.

This invention relates to an apparatus for the reduction of iron sands or concentrated ore, which is received at the plant in a finely pulverized condition.

The object of my invention is to produce a furnace or reduction plant which can be operated with gas such as is generated from the distillation of wood, or in the manufacture of coal into coke or peat or kindred substances.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a side elevation of a complete plant embodying my invention. Fig. 2 represents a section through the conveyor mechanism.

Similar numerals of reference indicate corresponding parts in the figures.

Referring to the drawings:—1 designates a bin of suitable size and construction to receive ore as it is delivered from the mines and from which the chute 2 conveys the same by means of a valve 3 to a chamber 4. From this chamber 4 the ore is delivered to a furnace 5 here shown in the preferred form as a rotary furnace, operated in any suitable manner, as by the gear 5'. This is preferably composed of a steel shell provided with a suitable lining, as brick, and is positioned to discharge into an air tight chamber 6, from which the ore is led to another rotating furnace 7 of similar construction to that before described, and operated in a like manner by gear 7'. The function

of the furnace 5 is to first heat the ore to a suitable temperature ready for delivery to the furnace 7, the exit end of which is located adjacent a chamber 8 of air tight construction and from which the discharge of ore is controlled by means of a valve 8'. The opening of this valve 8' allows the ore within the chamber 8 to pass to a conveyor 9, preferably of spiral type, operated by a revolving shaft driven by a pulley 11. This spiral conveyor 9 operates through a water jacketed chamber 10 in order to cool the ore as it passes through the conveyor.

12 designates crushing rollers suitably positioned adjacent the discharge end of the conveyor 9 and upon which the ore is deposited as it is delivered at regular intervals. These rollers crush the ore to a suitable fineness ready for separation, which preferably takes place by passing the ore over magnetic separators 13 from which it is delivered in the respective bins 14 and 15. These bins at the completion of the separation contain the two products produced, iron ore and dross. It will of course be understood that if the ore contains nonmagnetic particles of value, that other means of separation may be used, such taking the form of wet or dry concentration, as the case may be.

The gas used in preparing the ore is generated in a retort furnace 18 and is preferably made from the distillation of wood or coal. This gas is conducted at a high temperature under pressure through the conduit 16 into the chamber 8 and thus through the reduction furnaces to the furnace 5 in which it combines with a sufficient amount of air to maintain combustion and preheat the ore. The air necessary to support combustion in this furnace 5 is furnished by means of a blower 19 from which it is delivered by a pipe 20 to the furnace 5 and after passing therethrough is exhausted through the pipes 21 and 22.

In order to properly support the rotating furnaces 5 and 7 and permit the movement thereof, suitable roller bearings 23 are positioned at suitable intervals, as necessary.

It will be apparent that I have provided an apparatus in which the volatile substances such as sulfur, arsenic and phosphorus may be readily eliminated from the ore, after which the silicious gangue or dross may be mechanically separated from the metallic contents, thereby preventing any dan-

ger of melting them into the molten metal in its finished state, which is of course a great saving in both fuel and fluxes: In such ore as silicates, where a chemical union 5 exists between the silica and the metal, a separation cannot be effected without a direct fusion, but by means of my novel apparatus a mechanical separation of the silica can be effected, particularly in the case of an 10 iron oxid if the ore is reduced fine enough.

A still further advantage of my apparatus resides in the fact that the character of the gases can be altered as desired, that is for one condition an oxidizing roast may be 15 passed through the furnace, while in another a deoxidizing roast may be obtained.

It is further to be noted that the discharge from the roast furnace does not take place in contact with the outside air which is apt 20 to produce reoxidation, but it is discharged directly into a water jacketed chamber out of contact with the air, which is a very important feature in the treatment of iron ores. This feature may be further extended if 25 desired, by providing means to prevent exposure to the air while passing from the crushing rollers to the ore bin.

It will now be apparent that I have devised a novel and useful construction which 30 embodies the features of advantage enumerated as desirable in the statement of the invention and the above description and while I have in the present instance shown and described the preferred embodiment there- 35 of, which has been found in practice to give satisfactory and reliable results, it is to be understood that the same is susceptible of modification in various particulars without departing from the spirit or scope of the invention or sacrificing any of its advantages.

Having thus described my invention, what

I claim as new and desire to secure by Letters Patent, is:—

1. In a device of the character stated, a preheating furnace, a reducing furnace adjacent thereto, a chamber between said furnaces and having communication therewith, means to supply air to said chamber, a gas generator communicating with said second furnace, and a cooling device adjacent the 45 discharge end of one of said furnaces and through which the treated ore is passed.

2. In a device of the character stated, a rotatable preheating furnace, a hopper suitably mounted adjacent thereto and adapted 50 to communicate therewith, an air chamber vertically disposed and positioned to receive the discharge from said preheating furnace, a reducing furnace communicating with said air chamber, means to supply a 55 current of air to said air chamber, a gas generator having communication with said reducing furnace, and a cooling chamber into which the treated ore is discharged from said reducing furnace.

3. In a device of the character stated, a rotatable preheating furnace, a hopper suitably mounted adjacent thereto and adapted 60 to communicate therewith, an air chamber vertically disposed and positioned to receive 65 the discharge from said preheating furnace, a rotatably mounted reducing furnace communicating with said air chamber, means to supply a current of air to said air chamber, a gas generator having communication with 70 said reducing furnace, and a cooling chamber into which the treated ore is discharged from said reducing furnace.

GEORGE FREDERICK RENDALL.
